UNITED STATES PATENT OFFICE.

WILLARD B. GREENE, OF BOSTON, MASSACHUSETTS, ASSIGNOR TO AMERICAN OPTICAL COMPANY, OF SOUTHBRIDGE, MASSACHUSETTS, A VOLUNTARY ASSOCIATION OF MASSACHUSETTS.

EYEGLASSES.

1,264,295.

Specification of Letters Patent. Patented Apr. 30, 1918.

Application filed September 23, 1915. Serial No. 52,189.

To all whom it may concern:

Be it known that I, WILLARD B. GREENE, a citizen of the United States, residing at Boston, in the county of Suffolk and State 5 of Massachusetts, have invented certain new and useful Improvements in Eyeglasses, of which the following is a specification.

My invention relates to eyeglasses and has particular reference to holders or 10 retainers used in connection therewith.

My invention is particularly useful in connection with the fingerpiece type of eyeglasses as shown in my drawings and other types retained by nose gripping members 15 so that when said nose gripping members slip or fail to perform their intended purpose my improved holder will prevent dropping and breaking of the eyeglasses.

The leading object of my invention is the 20 provision of an improved method of connecting a chain or like flexible retaining member to a lens which will permit of the ready attachment or removal thereof, and will do away with the use of lens clips and 25 screws or other fixed or unsightly lens engaging devices.

Figure I is a perspective view of my construction attached to an eyeglass.

Fig. II is a sectional and end view illustrating 30 detachable connections at the end of the chain.

Fig. III is an enlarged view of a modification of my invention where it is not necessary to detach same from chain.

Fig. IV is another modification of my invention.

Fig. V is a further modification of my invention.

Fig. VI is an enlarged sectional view on 40 the line VI—VI of Fig. I.

Fig. VII is a sectional view illustrating another modification of my invention.

Fig. VIII is a sectional and end view of a further modification thereof.

Fig. IX illustrates the manner of applying one form of my holder to a lens.

My invention consists of an ear loop 1, or other suitable retaining means, connected by means of the loop 2 to one end of the 50 chin 3, the chain passing through the aperture 4 of the lens 5, and having at its other end the button or ball, 6, which can be either fixedly or detachably connected therewith, this ball or button being made larger than 55 the aperture in the lens.

The ear loop 1, having the ball tip 7, and the loop 2, made smaller than the diameter of the aperture 4 in the lens 5 can be easily inserted and then pulled through said aperture.

The chain 3, is then pulled through also till the ball or button, 6, rests against the outside edge of the aperture 4, as is clearly shown in Fig. VI.

This ball or button acts as a retainer when 65 the ear loop is attached to the wearer's ear and is the means of preventing accidental dropping and breaking of the eyeglasses should they become disengaged from the nose.

To remove my improved holder from the lens, it is merely necessary to reverse the 70 above described procedure, that is, by first pulling on the ball or button, 6, the chain will come out, then the ear hook 1.

It has been found that ladies sometimes prefer to use hair pins, etc., of various designs attached to the end of chain, 3, in place of the ear loop, 1, and on account of the size and shape of these forms of connections it is not always possible to pass 80 them through as small an aperture as will receive the ear hook type just described.

In order to provide for such cases, I have 85 made my improved buttons or balls, 6, detachably connected to one end of the chain, 3. The end of the chain has attached thereto a spring clip, or the like, which is passed through from the inner side of the aperture of the lens, then the spring clip is snapped 90 into engagement with the button, which is placed on the outer side of the lens.

Fig. II illustrates one detachable button made from a small tubular piece of metal, 8. A V shaped spring having the looped 95 end, 9, attached to the chain, is pressed into the tube, the bent portion, 10, on the other end of said spring locking with the shoulder, 11, on the inside of said tube to detachably connect the parts. A slot, 12, below the opening, 13, of the tube is made to provide enough space so that when pressing upon the end, 14, and loop, 9, of the spring, the same can be easily withdrawn or detached from the tubular piece 8. The slot 105 also prevents rotation inside of the tube. The tube is spread and spun at the other end to provide a retaining head, 15.

Fig. VII is a slight modification in which the tube, 8, has the interior groove, 16, into 110

which a looped member, 17, having its ends, 18, bent outwardly at right angles, is pressed, said end, 18, snapping into the groove, 16, substantially as illustrated.

5 In Fig. VIII is illustrated a ball, 6, which may be provided with a neck, 19, having an oblong shaped aperture, 20. One end of this aperture is provided with lip, 21, with which, the shoulder, 22, of the looped spring member, 23, will engage when said spring is pressed into the aperture, 20.

In Figs. III, IV, and V, I have illustrated different shapes of buttons in which the ring, 24, may be soldered direct to the button, 6, or the neck, 19, between rings, 24, and button, 6, or may be integral therewith.

15 It will further be understood that these and various other shapes may be employed with the detachable chain connection in place of the fixed ring if desired.

I claim:

1. An attachment for ophthalmic mountings including an ear loop having an eye, and a flexible connecting member having one end secured to the eye and having secured 25 on the opposite end a ball of enlargement of greater diameter than the eye whereby the device may be applied to a drilled lens by threading of the loop, eye and flexible con-

nexion through the aperture in the lens, 30 and the ball will engage the face of the lens adjacent the aperture to connect the parts substantially as and for the purpose described.

2. In an attachment for ophthalmic mountings including a nose bridge supporting lenses at each end thereof, the combination with an ear loop having portions adapted to fit both behind and in front of the ear to retain the loop in position on the ear and one end of said loop terminating in an eye, of a flexible connecting member having one end secured to the eye and having secured 35 on the opposite end a ball or enlargement of greater diameter than the eye whereby the device may be inserted by threading of the loop, eye and flexible connection through an aperture in one of the lenses whereby the ball will engage the face of the lens adjacent the aperture to connect the parts substantially as and for the purpose described.

40 In testimony whereof I affix my signature in the presence of two witnesses.

WILLARD B. GREENE.
